THREAD SEPARATING THREAD HOLDER

Oscar V. Payne, Leicester, Mass., assignor to
Crompton & Knowles Loom Works, Worcester,
Mass., a corporation of Massachusetts

Application April 1, 1944, Serial No. 529,146

13 Claims. (Cl. 139—247)

This invention relates to thread holders for looms and it is the general object of the invention to provide a holder which will tension two different types of threads and also keep them separated.

In the weaving of certain fabrics it is customary to use a decorative stripe of one type of weft, such as rayon or an artificial yarn, introduced at intervals in the body of the fabric which is made of a different yarn, such as coarse woolen or cotton. It is desirable to keep the two types of threads separated so that the waste can be reclaimed. Heretofore, thread holders have been made in such a way that all of the weft ends were led to a common point where they become entangled to such an extent that the two different types of threads could not economically be separated. It is an important object of my present invention to provide a thread holder having two different sets of traveling surfaces one of which engages one type of yarn and the other of which engages the other type of yarn.

In my prior patent No. 1,842,731 there is set forth a type of thread holder having a pair of geared members between the teeth of which extend the weft ends of reserve bobbins held in a magazine. As shown in the patent the gears are on that side of their support opposite the magazine and the support serves as a guide to hold the threads in proper position for engagement with the gears. It is a further object of my present invention to supply an additional pair of gears on that side of the support adjacent to the magazine and mount a thread guide over them which will guide the threads downwardly for correct engagement with the gears.

In geared thread holders of the type mentioned each gear has its own shaft and it is a further object of my present invention to add an additional gear to each shaft and drive the shafts by mechanism mounted within the holder in such a way that a common drive mechanism will suffice for both pairs of gears.

The rayon yarns are generally of small diameter and the total number of weft ends from the rayon bobbins forms a small bundle. The weft ends from the woolen or cotton bobbins on the other hand are of much larger diameter and form a relatively large bundle. When the magazine has a full supply of coarse yarn the corresponding bundle of weft ends will be so large as to interfere with the proper operation of the associated pair of gears if the latter are set for proper operation with a few threads only. It is

another object of my present invention to provide a resilient mounting for at least one of the gears which engages the coarse yarn so that it can accommodate itself to the size of the bundle of yarns which it engages. As the number of weft ends diminishes the resiliently mounted gear moves toward its mate to provide the proper drive for the fewer number of threads. This variation between the distance of the gears for 5 the coarse yarn occurs while the gears for the rayon threads remain at a fixed distance apart. The drive for the two pairs of gears is such, however, that it is effective to actuate the gears for both types of yarns regardless of the distance between the gears for the coarse yarn.

In weft replenishing looms it is customary to cut the thread of a transferred bobbin at the selvage several picks after transfer. A coarse thread extending from the outer gears when cut 10 might fall on the inner pair of gears and become entangled with the finer yarns unless provisions were made to hold such a thread away from the rayon yarns. It is another object of my invention to provide a guard, preferably formed as part of 15 the aforesaid guide, which extends inwardly beyond the inner gears to hold a cut coarse thread spaced from the finer yarns.

By mounting the pairs of gears on opposite sides of the support or casing which contains the 20 drive mechanism I effect sufficient separation between the two types of yarn so that they can be gathered independently of each other, thereby simplifying the process of reclaiming.

With these and other objects in view which will 25 appear as the description proceeds, my invention resides in the combination and arrangement of parts hereinafter described and set forth.

In the accompanying drawings, wherein a convenient embodiment of my invention is set forth:

40 Fig. 1 is a front elevation of a portion of the loom having my improved thread holder applied thereto and indicating the magazine as supplied with fine and coarse weft bobbins,

45 Fig. 2 is an enlarged side elevation looking in the direction of arrow 2, Fig. 1, showing the gears for the coarse wefts,

Fig. 3 is an enlarged side elevation looking in the direction of arrow 3, Fig. 1, and showing the gears which cooperate with the fine or small 50 weft ends,

Fig. 4 is a horizontal section on line 4—4 of Fig. 2 showing the two shafts each having a gear on each end thereof,

55 Fig. 5 is an enlarged plan view looking in the direction of arrow 5, Fig. 1, and showing the

guide for the fine wefts and guard for the coarse wefts.

Fig. 6 is an enlarged side elevation of one of the gears for the coarse weft and the supporting shaft therefor.

Fig. 7 is a vertical longitudinal section on line 7-7 of Fig. 6.

Fig. 8 is a diagrammatic side elevation of the gears for the coarse weft showing a large bundle of weft ends between them.

Fig. 9 is a view similar to Fig. 8 but showing a reduced number of coarse weft ends between the gears, and

Fig. 10 is a diagrammatic front elevation similar to part of Fig. 1 showing the relation of my thread holder and the weft ends which have been cut at the selvage after transfer.

Referring particularly to Fig. 1, I have shown a loom frame F having a lay L across which travel several shuttles at least one of which, shown at S, carries fine weft, such as rayon. When depleted shuttle S is replenished by reserve bobbins BF wound with fine weft, the other shuttles not shown are replenished by reserve bobbins BC wound with coarse weft. The bobbins are mounted in the magazine M and are fed down to transfer position in well-known manner. Picking mechanism P of usual form is actuated in well-known manner to drive the shuttles one at a time back and forth across the lay, each of the shuttles arriving periodically in transfer position under the magazine M.

In order that the shuttles may be properly threaded following replenishing operations it is necessary to provide an anchorage for the weft ends of transferred bobbins. To accomplish this general purpose I use a thread holder H located adjacent to the outer end of that part of the lay near the magazine. This thread holder is mounted on the front of an arm I0 which is supported on the magazine in such a way that the arm and holder will vibrate during loom operation.

The holder comprises a box-like structure or casing 15 on the inner vertical wall 16 of which are mounted front and back shafts 17 and 18, respectively. A ratchet wheel 20, see Fig. 4, is secured to shaft 17 in a manner to be described and is driven by a pawl 21, see Fig. 3, moving with a weighted member 22 located within the casing 15. During loom operation the weight vibrates with respect to the casing and the relative movement between the pawl and the ratchet causes the latter to rotate, thereby turning shaft 17.

The matter thus far described is of well-known construction and may be used and operated as set forth in my aforesaid patent.

In carrying my present invention into effect I provide means by which the holder H can tension each of two groups of threads and at the same time keep the groups separated. To accomplish this result I provide two pairs of smooth toothed gears, one pair for the coarse yarn on the outer side of the casing and the other pair on the opposite or inner side of the casing for the fine yarns. The front and back gears of the outer pair are designated at G1 and G2, respectively, while the corresponding gears of the inner pair are designated at G3 and G4, respectively. Front gears G1 and G3 are on front shaft 17, while rear gears G2 and G4 are on rear shaft 18.

As shown in Fig. 4 a nut 25 on shaft 17 forces gear G3 against a sleeve 26 surrounding shaft 17, and the sleeve in turn forces the ratchet wheel 20 against an enlarged part 27 of shaft 17. Part 27

of shaft 17 turns in a bearing 28 on wall 16 shorter than shaft part 27. By reason of nut 25 it will be seen that shaft 17, gear G3, and ratchet wheel 20 are turned as a unit by the pawl.

5 The other or outer end of shaft 17 is formed as indicated in Figs. 6 and 7 and is connected to the gear G1 by a resilient drive so constructed as to permit lateral displacement of gear G1 relatively to gear G2. Gear G1 has a bushing 30 driven in one end of the bore 31 thereof, preferably the outer end, and this bushing receives an end 32 of a coil spring 33 which is wrapped around the shaft 17 and then secured thereto as at 35, see Fig. 7. The internal diameter of the bushing 30 is larger than the adjacent part of shaft 17 and the spring and the gear G1 can therefore move laterally with respect to shaft 17.

The spring 33 is sufficiently strong to provide a driving connection between shaft 17 and the gear G1. The rear shaft 18 turns in a bearing 40 adjustable on wall 16 toward and from shaft 17 and normally held stationary, as at 41. The reduced ends 42 and 43 of shaft 18 carry the gears G2 and G4, respectively, and the latter are clamped by nuts 44 against the larger central part 45 of shaft 18. This part 45 is slightly longer than bearing 40 to permit free rotation of shaft 18 and gears G2 and G4 as a unit.

30 The inner pair of gears G3 and G4 have their free ends facing the magazine and are therefore unable of themselves to keep weft ends between them since the threads would tend to pull out. In order to cause the fine or rayon yarns to pass down between the gears G3 and G4 I use a form 35 of guide shown more particularly in Figs. 3, 5 and 10. This guide may be formed as a plate 50 held as at 51 to the casing 15. The plate has two inclined edges 52 and 53 which meet at a point substantially over the mid-point between gears G3 and G4 and form a shallow notch 54. The notch is vertically over a point which is intermediate between the free ends of the gears G3 and G4 and the casing 15 so that any threads hanging 40 downwardly from the notch will pass between the inner gears. The plate 50 has the forward part 55 thereof bent up in such a manner as to facilitate passage of the fine threads thereunder. Plate 50 has a slot 56 therein open at the front and extending generally parallel to the length of casing 15. A bar 57 defines the left edge of the slot and is connected at the rear end thereof to the plate. The outer side of the slot 56, Fig. 5, is defined by an edge 58 which is nearer the magazine than the free ends of the gears G3 and G4 while the inner side of the bar 57 has an edge 59 which is farther from casing 15 than is edge 58, all for 45 purposes to be explained.

50 As shown in Fig. 10 a weft end remaining after a transfer extends from the thread holder to the cloth 60 and is eventually cut by the selvage cutter 61 several picks after transfer. When the left end of the thread, designated by dot and dash line A in Fig. 10, is cut it falls and would lie across the gears G3 and G4 unless provision were made to keep it away from them. This is particularly true of the coarse threads which are held by the outer pair of gears G1 and G2. The plate 50, however, acts to hold the cut ends in proper position, as will appear hereinafter.

55 In operation, the magazine may first be filled with the coarse bobbins BC and their weft ends WC are led over the plate 50 and the casing 15 to a point between the gears G1 and G2. The latter gears may then be turned manually in order to insure correct placement of the weft

ends WC. The fine yarn bobbins-BF can then be inserted in the magazine and their weft ends WF led under bar 57 and then over the plate 50 and drawn toward notch 54, after which they are released and fall onto one or another of the gears G3 or G4. Rotation of the latter by an additional turning of gears G1 and G2 will draw the fine yarns between their gears.

During loom operation vibration of weight 22 will cause the turning of shafts 17 and 18 in a manner very similar to that set forth in my prior patent and both the fine and coarse wefts will be tensioned. When a shuttle carrying a coarse weft is to be replenished one of the bobbins BC will move downwardly from its group and the weft end WC corresponding thereto will separate from the group of threads above it and extend over the casing 15 and plate 50 to the newly replenished shuttle. Upon subsequent cutting this coarse thread will fall over bar 57 and hang down as at 60' from edge 59.

When the shuttle carrying the fine weft is to be replenished one of the bobbins BF will drop from its group to transfer position and carry the corresponding weft end WF downwardly, and upon subsequent cutting at the selvage this thread will fall and hang down from edge 58, as at 61', Figs. 5 and 10 and be spaced from the coarse weft previously dropped.

When the magazine is first filled with bobbins BC their weft ends will form a large bundle lying between the gears G1 and G2. Under these conditions the spring 33 will yield sufficiently to permit gear G1 to move away from gear G2, see Fig. 8, and the outer pair of gears will therefore be able to rotate despite the presence of a large volume of weft ends between them. As weaving continues and the bobbins BC are used up in successive replenishing operations the bundle formed by their weft ends becomes smaller. Under these conditions the spring 33 moves back to its normal position, thereby carrying the gear G1 toward gear G2 to establish proper frictional conditions between these gears and the diminished number of coarse weft ends. The spring 33 is therefore seen to permit the gear G1 to accommodate itself to the mass or size of the bundle of weft ends between it and gear G2.

Throughout the self-adjusting operation of the gear G1 the gears G3 and G4 will rotate at a fixed distance from each other, no compensation being needed with respect to these gears because the yarns with which they co-act are small. It will be apparent, however, that if desired one or the other of the gears G3 and G4 could have the same character of mounting as that shown for gear G1. But I do not deem it necessary herein to show a yielding mounting for either of the gears G3 or G4. It will also be apparent that the outer gears G1 and G2 could be used for the fine yarns and the inner gears G3 and G4 used for the coarse yarns if appropriate change were made in the mounting of one or another of the gears G3 and G4 to permit the self-adjustment already described with respect to gear G1. The resilient drive for gears G1 will not be necessary if the yarns WC are of medium size, and so far as certain features of the invention are concerned both the outside gears may rotate on fixed axes.

The guide plate 50 is so disposed as not to interfere with the coarse weft ends during transfers, involving the latter. It will be evident from Fig. 1 that the fine yarns are arranged in a group on one side of the holder while the coarse yarns are similarly grouped on the opposite side thereof

and for this reason it is possible to separate the two types of yarn for purposes of reclamation. It is evident that if all the weft in the magazine is coarse, half of the weft ends can be placed between the outer gears and the other half between the inner gears. While I have shown a vibration motor I am not limited to its use as means for turning the gears.

From the foregoing it will be seen that I have provided a simple form of thread holder so constructed that it will tension and at the same time separate two different groups of weft threads. The casing or support 15 serves as a separator for the two different groups of weft ends due to its position between the inner and outer pairs of gears. Furthermore, the guide for the fine wefts serves to hold the latter in position for cooperation with the inner pair of gears. Also, the guard for the coarse weft which has been cut at the selvage prevents entanglement thereof with the fine wefts. A common drive mechanism located within the casing 15 suffices to drive both sets of thread gears, and the spring mounting for the front gear G1 permits the latter to adjust its position with respect to gear G2 as the bundle of coarse weft ends diminishes. This relative adjustment of the outer gears takes place while the single driving mechanism continues to operate and without disturbance of the gears for the fine weft. The spaced edges 58 and 59 effect separation of the weft ends which are cut at the selvage. By the use of the invention set forth herein it is possible to use two different characters of weft in a loom and keep them separated for the purpose of simplifying reclamation, or divide the weft ends into two different groups when all the ends are coarse.

Having thus described my invention it will be seen that changes and modifications may be made therein by those skilled in the art without departing from the spirit and scope of the invention and I do not wish to be limited to the details herein disclosed, but what I claim is:

1. In a thread holder for a weft replenishing mechanism from which two groups of weft ends extend toward a support spaced from the mechanism, a pair of geared weft end engaging units rotating on said support and extending on opposite sides thereof and tending to draw said weft ends away from said mechanism, a guide to direct one of said groups of weft ends toward said geared units on one side of said support, and a second guide to direct the other group of weft ends toward said geared units on the opposite side of said support, said support acting as a separator for said groups.

2. In a thread holder for a weft replenishing mechanism from which two groups of weft ends extend toward a support spaced from the mechanism, a pair of geared weft end engaging units extending on opposite sides of said support and rotating on the latter about axes extending toward said replenishing mechanism and tending to draw said weft ends away from the mechanism, said geared units having parts extending from said support away from said mechanism and having other parts extending from said support toward said mechanism, a thread guide directing the threads of one of said groups toward the first named parts of said geared units, and a second thread guide directing the threads of the other group toward said other parts of the geared units, said support separating said groups as the latter pass between their respective parts of said units.

3. In a thread holder for a weft replenishing mechanism from which two groups of weft ends extend toward a support spaced from the mechanism, a pair of geared weft end engaging units rotating on said support and tending to draw said weft ends away from the mechanism, said groups of weft ends passing between said units and depending therefrom, said units having free ends extending from the support away from said mechanism and having other free ends extending from the support toward said mechanism, a guide on said support directing the weft ends of one of said groups toward the first named free ends of the geared units, and a second guide on said support directing the weft ends of the other group toward said other free ends of the geared units, said support separating the depending groups from each other.

4. In a thread holder for a weft replenishing mechanism from which two groups of weft ends extend toward a support spaced from the mechanism, a pair of weft end engaging geared members rotatably mounted on the support and extending away from said mechanism, a guide directing one of said groups of weft ends toward said pair of geared members, a second pair of geared members mounted on said support and extending toward said mechanism, a second guide directing the other groups of weft ends toward said second pair of geared members, and means causing rotation of said geared members on said support in a direction tending to draw said weft ends away from said mechanism.

5. In a thread holder for a weft replenishing mechanism from which two groups of weft ends extend toward a support spaced from the mechanism, a pair of shafts rotatably mounted on said support and extending on opposite sides of the latter, a pair of thread engaging geared members mounted one on each of said shafts and located on that side of the support opposite the mechanism and engaging one of said groups of weft ends, a second pair of geared members also mounted one on each of said shafts and located on that side of the support adjacent to the mechanism and engaging the other group of weft ends, and means to cause rotation of said geared members during loom operation in such directions as to cause said geared members to tend to draw said weft ends away from said mechanism.

6. In a thread holder for a weft replenishing mechanism from which a group of weft ends extend toward a support spaced from the mechanism, a pair of geared units engaging said weft ends and rotating on said support about axes extending toward said replenishing mechanism and tending to draw said weft ends away from the mechanism, said geared units extending from the support toward the mechanism and having free ends facing the latter, and a guide having a weft end-guiding surface located farther from said mechanism than said free ends and directing said group of weft ends downwardly toward said geared units.

7. In a weft replenishing loom having a group of weft ends extending from a magazine toward a support and having a thread extending from said support to the adjacent selvage, geared members rotating on said support and tending to draw said weft ends and thread away from said magazine, said geared members extending from the support toward said magazine and having free ends facing the latter, a thread guide above said free ends and having two edges one of which is farther from said magazine than said free ends

and guides said weft ends and thread toward said geared members and the other edge of which is nearer the magazine than said free ends and holds said thread away from said geared members after said thread is cut at the selvage and falls over said other edge.

8. In a weft replenishing mechanism having two groups of reserve bobbins from which two groups of weft ends extend to a thread holder, 10 any of said weft ends involved in a replenishing operation subsequently extending from the thread holder to the selvage where it is cut, two pairs of geared members rotating on said thread holder and tending to draw said weft ends away from the mechanism, one pair being on that side of the holder remote from the mechanism and engaging one of said groups and the other pair being on that side of the holder adjacent to the mechanism and engaging the other of said groups, 15 and guide means extending over the second pair of geared members and effective to hold any of said weft ends which are cut at the selvage away from said second pair of geared members.

9. In a weft replenishing mechanism having 25 two groups of reserve bobbins from which two groups of weft ends extend to a thread holder, any of said weft ends involved in a replenishing operation subsequently extending from the thread holder to the selvage where it is cut, two pairs of geared members rotating on said thread holder and tending to draw said weft ends away from the mechanism, one pair being on that side of the holder remote from the mechanism and engaging one of said groups and the other pair 30 being on that side of the holder adjacent to the mechanism and engaging the other of said groups, and guide means extending over the second pair of geared members and effective to hold any weft end engaged by said one pair of geared 35 members away from said second pair of geared members after said weft end is cut at the selvage.

10. In a thread holder for a weft replenishing mechanism from which two groups of weft ends extend toward a support spaced from the mechanism, 45 a pair of weft end engaging geared members rotatably mounted on the support and extending away from said mechanism, a guide directing one of said groups of weft ends toward said pair of geared members, a second pair of 50 geared members mounted on said support and extending toward said mechanism, a second guide directing the other group of weft ends toward said second pair of geared members and preventing engagement of said first group of weft ends 55 with said second pair of geared members, and means causing rotation of said geared members on said support in a direction tending to draw said weft ends away from said mechanism.

11. In a weft replenishing loom having a magazine 60 from which two groups of weft ends extend to a thread holder, any of said weft ends involved in a replenishing operation of the loom subsequently extending from the thread holder to the selvage where it is cut, a pair of geared members 65 for one of said groups of weft ends located on that side of the thread holder remote from the magazine, a second pair of geared members on that side of the thread holder adjacent to the magazine for the other group of weft ends, and 70 a guide over the second pair of geared members effective to hold a weft end belonging to either group away from said second pair of geared members when said weft end falls after cutting at the selvage.

12. In a weft replenishing mechanism having

two groups of reserve bobbins from which two groups of weft ends extend to a support, a pair of geared members engaging one of said groups of weft ends and mounted on that side of said support remote from the replenishing mechanism and rotating in a direction to draw the ends of said one group of weft ends away from said replenishing mechanism, a second pair of geared members engaging the other of said groups of weft ends and mounted on that side of said support adjacent to the replenishing mechanism and rotating in a direction to draw the weft ends of the other group away from said mechanism, and means preventing engagement of the ends of said one group of weft ends with said second pair of geared members.

13. In a weft replenishing loom having a magazine from which two groups of weft ends extend

5 to a thread holder, any of said weft ends involved in a replenishing operation of the loom subsequently extending from the thread holder to the selvage where it is cut, a pair of geared members for one of said groups of weft ends located on that side of the thread holder remote from the magazine, a second pair of geared members on that side of the thread holder adjacent to the magazine for the other group of weft ends, and a guide over the second pair of geared members effective to hold a weft end belonging to either group away from said second pair of geared members when said weft end falls after cutting at the selvage, and also separate a cut weft end belonging to one group from a cut weft end belonging to the other group.

OSCAR V. PAYNE.
